UNITED STATES PATENT OFFICE.

CHARLES BOOZE, OF BUFFALO, NEW YORK, ASSIGNOR TO M. H. BIRGE & SONS, OF SAME PLACE.

DESIGN FOR WALL-PAPER.

SPECIFICATION forming part of Design No. 23,602, dated August 28, 1894.

Application filed August 3, 1894. Serial No. 519,374. Term of patent 3½ years.

To all whom it may concern:

Be it known that I, CHARLES BOOZE, a citizen of the United States, residing at Buffalo, in the county of Erie and State of New York, 5 have invented and produced a new and original Design for Wall-Paper, of which the following is a specification.

The design consists of a series of ornamental scrolls forming large panels with sprays 10 of ornamental leaves, and groups of flowers and leaves arranged in the said panels as represented in the accompanying drawing. The border or upper portion of the design is formed of a series of ornamental scrolls forming ornamental panels with ornamental 15

leaves, and flowers and leaves arranged in said panels, and small groups of flowers and leaves outside of said panels as shown in the drawing.

What I claim is—

1. The design for wall paper herein shown and described.
2. In the design for wall paper the border herein shown and described.

Witness my hand this 31st day of July, 25 1894.

CHARLES BOOZE.
